DESIGN FOR A DRESS

Blanche Lahn, New York, N. Y., assignor to Franklin Simon & Co., Inc., New York, N. Y.

Application January 7, 1935, Serial No. 54,751

Term of patent 3½ years

To all whom it may concern:

Be it known that I, Blanche Lahn, a citizen of the United States of America, residing in Manhattan, county of New York, and State of New York, have invented a new, original, and ornamental Design for a Dress, of which the following is a specification, reference being had to the accompanying drawing, forming part thereof, wherein,

I claim:

The ornamental design for a dress, substantially as shown.

BLANCHE LAHN.
